UNITED STATES PATENT OFFICE.

ADOLF BAYER, OF BROOKLYN, NEW YORK.

REVOLVING-PISTON EXPLOSIVE-ENGINE.

No. 867,782.

Specification of Letters Patent.

Patented Oct. 8, 1907.

Application filed March 9, 1907. Serial No. 361,619.

To all whom it may concern:

Be it known that I, ADOLF BAYER, a subject of the Emperor of Austria-Hungary, applicant for citizenship of the United States, residing at Brooklyn, in the county of 5 Kings and State of New York, have invented certain new and useful Improvements in Revolving-Piston Explosive-Engines, of which the following is a specification.

My invention relates to revolving piston explosive engines, and its object is to produce an internal combustion consuming gasoline spray or gas, and having parts of special construction and particular arrangement whereby it is believed that greater economy of construction is attained, and the necessary parts are 15 reduced to a minimum number and weight with reference to the power given out by the engine in regular service.

I accomplish the stated object by fashioning and associating the constituent elements substantially as illustrated in the accompanying drawings, of which

Figure 1 represents a side view. Fig. 2 is a vertical, longitudinal section. Fig. 3 is a horizontal longitudinal section of the pump cylinder and piston casing, the other parts being shown mainly in full lines.

Like reference numbers are used to denote the same parts throughout the specification and claims.

Upon a suitable bedplate 1, is supported the cylinder casing, which comprises the annular frame 2, and the circular side plates 3 and 4. The side plates are provided with bearings 5 and 6 for the transverse engine shaft 7. The revolving cylindrical piston 8 is secured eccentrically upon the shaft 7 within the casing, as illustrated in Fig. 2.

The frame 2 of the casing is provided with an inwardly-opening air valve 9 by way of which external air may enter the casing, and an outwardly-opening exhaust valve 10, both of those valves being again referred to in this description.

To compress and supply the explosive mixture to the engine, I construct the pump cylinder 11, which is secured to the piston casing and projects radially and horizontally from the frame 2 as shown in Figs. 1 and 2. It is my practice, usually, to support the pump cylinder upon the bedplate by means of the pillar 12.

Within the pump cylinder is the pump piston 13, and the piston rod 14 passes through the pump piston and through the head of the pump cylinder to the outside in one direction, and in the other direction the rod extends through the guide bearing 15, and into the throat 16 forming part of frame 2. From Figs. 2 and 3, it will be learned, that the end of the piston rod is bored axially to receive movably the extension rod 17. At its outer end the extension rod is secured to a crosshead 18, and encircling the extension rod between the crosshead and the end of piston rod 14 is a helical spring 19. The crosshead bears the suitably mounted trans-

verse roller 20, which is kept normally in contact with the revolving piston 8. The office of the roller is, while in constant contact with the revolving piston, to cause as little friction as possible by reason of such contact, 60 introducing rolling rather than sliding friction. The office of the spring 19 is to extend the movable rod 17 and the crosshead into contact with the revolving piston when, as is the case at the beginning of the movement, the revolving piston leaves the socket or seat 20 65 in frame 2 faster than piston rod 14 is drawn towards the left by the side bars operated by the disks and rollers hereinafter described.

To keep the crosshead always in the same position with respect to its socket or seat in order that it may 70 enter the same truly each time it returns from its excursion into the casing, I provide the two guide rods 21 and 22 as best shown in Fig. 3, one upon each side of the piston rod. The guide rods have one end secured to the crosshead and pass outwardly through the bearings 23 and 24 formed in frame 2.

The head of the pump cylinder is provided with the hood 25, that covers the suction valve 26 and the inlet valve 27 by way of which the gasoline or gas enters and is explosively mixed with air drawn in through 80 the perforations 28 shown in the end of the hood. The head of the pump cylinder also carries a second hood 29 which possesses a lateral extension 30, and also covers an outwardly-opening valve 31. When the valve 31 opens, by reason of internal pressure, the pump cylinder is in communication by way of the extension 30 of the hood with passage 32 formed lengthwise in the upper wall of the cylinder 11, and leading to and opening into the port 33 in the frame 2 of the casing of the revolving piston, and through which the exploded gases 90 reach the piston and actuate it. It is my practice to control the passage 32 by means of a cut-off valve 34 located near the port 33. This valve is necessary in order to close the passage while the explosive gases are being compressed therein as hereinafter set forth.

Valve 34 is operated by raising and lowering it, and those movements are effected by means of the curved arm 35, one end of which is pivotally connected with the valve 34 and the other end is pivotally secured to the circular side plate 5 as shown in Fig. 1. The arm 100 35 is provided with an enlarged portion or cam 36 having curved surfaces leading to it and from it as indicated, and it is arranged to be encountered by a like enlargement 37 formed upon the link frame portion 38 of the sliding side-bar 39, as best shown in Fig. 1.

There are two sliding side-bars, arranged horizontally lengthwise near the pump cylinder and casing 2, one on either side thereof as shown in Fig. 3. Side-bar 39, already mentioned, is movably supported and guided in the bearings 40, 41 and 42. The companion side-bar on the other side, as best shown in Fig. 3, is marked 43, and its bearings are referred to by the num-

bers 44, 45 and 46. One end of each of the side-bars 39 and 43 is secured rigidly to the transverse end bar 47, best shown in Fig. 3, and to the end bar 47 the piston rod 14 is likewise connected. The side-bars are movable as indicated lengthwise in two directions. Towards the left hand they are moved by the action of the disks 48 and 49 both fixed upon the outer ends of the engine shaft 7, the disks engaging the rollers 50 and 51 shown in Figs. 1 and 3 as rotatably borne by the side-bars in contiguity with the disks. Towards the right, the side-bars are carried by the movement of the piston rod 14 with which they are connected as already explained.

The operation of my invention may be described as follows: The flywheel 52 being suitably rotated by hand or otherwise, a charge of the explosive mixture is drawn into the pump cylinder by way of the valves 26 and 27, and the return of the piston 13 compresses the gaseous body into the passage 32. At the same time, the two cams or enlargements 36 and 37 upon the pivoted arm 35 and side-bar 39 come into contact, with the result that the valve 34 is raised quickly, and the spring fingers 53 and 54 are separated, breaking the circuit from the battery 55, and, by the agency of a spark coil 56, a spark is generated at the spark plug 57 and the gaseous charge exploded. The products of the explosion rushes through the port 33 in the frame 2 and acts upon the revolving piston 8, which is forced in the direction of the arrow. The hot gases continue as they expand to press and drive the piston 8 until the force of the explosion is exhausted, and as the piston continues its movement the expanded gases are forced out by way of the exhaust valve. As the piston 8 leaves the position shown in Fig. 2, it begins to draw away from the port 33, and the force of the explosion driving the gases through the port 33 would shoot at least a portion past the piston thus wasting its effort. But, as the piston 8 revolves, as has been explained, the engagement of the disks, and the rollers 50, 51, on the side-bars acting through the piston rod keep the extensible crosshead in contact with the revolving piston. By this construction the gases are temporarily confined between the frame and revolving piston immediately above the crosshead 18, and their pressure exerted in useful effect upon the piston until they have fully expanded. As the movement continues, a new charge is drawn into the pump cylinder and compressed by the pump piston 13 under the impulse stored up in the revolution of the flywheel, and, as will be understood, an explosion takes place for each revolution of the engine shaft. After the engine is shut down, if by reason of internal condensation the pressure within the cylinder casing drops below that of the air, the pressure is equalized by way of the inlet valve 9.

Having now described my invention and explained the mode of its operation, what I claim is—

1. In an explosive engine, the combination with an engine shaft, of a cylindrical revolving piston, a casing enclosing the said piston, a pump cylinder projecting radially from the said casing, a piston rod passing axially through the pump cylinder to the outside in one direction and into the said casing in the other direction, a pump piston se-

cured to the said rod, a crosshead secured to the end of the said rod and movable by the rod into the said casing, and external devices operated by the engine shaft and arranged to act upon the said piston rod whereby the said crosshead is moved in correspondence with the said revolving piston, substantially as described. 65

2. In an explosive engine, the combination with an engine shaft, of a cylindrical revolving piston, a casing enclosing the said piston, a pump cylinder projecting radially from the said casing, a piston rod passing axially through the pump cylinder to the outside in one direction and into the said casing in the other direction, a pump piston secured to the said rod, a crosshead secured to the end of the said rod and movable by the rod into the said casing, a spring and means constructed and arranged to advance the crosshead yieldingly against the said revolving piston, and external devices operated by the engine shaft and arranged to act upon the said piston rod whereby the said crosshead is moved in correspondence with the said revolving piston, substantially as described. 70 75 80

3. In an explosive engine, the combination with an engine shaft, of a cylindrical revolving piston, a casing enclosing the said piston, a pump cylinder projecting radially from the said casing, a piston rod passing axially through the pump cylinder to the outside in one direction and into the said casing in the other direction, a pump piston secured to the said rod, a crosshead secured to the end of the said rod and movable by the rod into the said casing, sliding side bars, bearings adapted to support the said bars movably, a cross-bar connecting the said bars and piston rod, and means operated by the said engine shaft and arranged to reciprocate the side bars and piston rod whereby the said crosshead is moved in correspondence with the said revolving piston, substantially as described. 85 90 95

4. In an explosive engine, the combination with an engine shaft, of a cylindrical revolving piston, a casing enclosing the said piston, a pump cylinder projecting radially from the said casing, a piston rod passing axially through the pump cylinder to the outside in one direction and into the said casing in the other direction, a pump piston secured to the said rod, a crosshead secured to the end of the said rod and movable by the rod into the said casing, a spring and means constructed and arranged to advance the said crosshead yieldingly against the said revolving piston, sliding side bars, bearings adapted to support the said bars movably, a cross-bar connecting the said bars and piston rod, and means operated by the said engine shaft and arranged to actuate the side bars and piston rod whereby the said crosshead is moved in correspondence with the said revolving piston, substantially as described. 100 105 110

5. In an explosive engine, the combination with an internally cylindrical casing, of a transverse engine shaft passing centrally through the casing, a cylindrical revolving piston eccentrically secured upon the engine shaft and arranged to sweep the interior of the casing, a crosshead provided with extensible devices, and means operated by the said engine shaft whereby the said crosshead is moved in the casing in correspondence with the said revolving piston, substantially as described. 115 120

6. In an explosive engine, the combination with an internally cylindrical casing, of a transverse engine shaft passing centrally through the casing, a cylindrical revolving piston eccentrically secured upon the engine shaft and arranged to sweep the interior of the casing, a crosshead provided with extensible devices, a pump having a piston rod connected with the said crosshead, and means operated by the said engine shaft, whereby the said piston rod and crosshead are moved in correspondence with the movement of the revolving piston, substantially as described. 125 130

In testimony whereof I affix my signature in presence of two witnesses.

ADOLF BAYER.
